[57] CLAIM

The ornamental design for a limit adjusting screw, as shown and described.

DESCRIPTION

FIG. 1 is a front elevational view of a limit adjust screw showing my new design, the side opposite being substantially a mirror image;

FIG. 2 is a side elevational view thereof, the side opposite being substantially a mirror image;

FIG. 3 is a top plan view taken in the direction of the arrows on line 3—3 of FIG. 1;

FIG. 4 is a bottom plan view taken in the direction of the arrows on line 3—3 of FIG. 1;

FIG. 5 is a cross sectional view taken in the direction of the arrows on line 5—5 of FIG. 1.
